(57) **CLAIM**

The ornamental design for a pluggable networking device, substantially as shown and described.

DESCRIPTION

FIG. 1 is a front perspective of a pluggable networking device, showing our new design;

FIG. 2 is a rear perspective view thereof;

FIG. 3 is front view thereof;

FIG. 4 is rear view thereof;

FIG. 5 is a right side view thereof;

FIG. 6 is a left side view thereof;

FIG. 7 is top view thereof; and,

FIG. 8 is a bottom view thereof.

The broken lines in the figures illustrate portions of the pluggable networking device that form no part of the claimed design.
